LIMITER CIRCUIT FOR FREQUENCY MODULATION RECEIVERS

Carl E. Atkins, Oak Park, Ill., assignor to Tung-Sol Lamp Works, Inc., Newark, N. J., a corporation of Delaware

Application January 7, 1942, Serial No. 425,843

11 Claims. (Cl. 178—44)

The present invention relates to radio reception and more particularly to the reception of frequency modulated waves and comprises a novel limiter circuit for incorporation into radio receivers of this general type. In frequency modulated radio reception, as distinguished from amplitude modulated radio reception, the receivers should respond only to the rate of change of angle of the incoming wave, that is to the relative frequency variation of the wave and should not be responsive to excessive amplitude variations of the wave. Accordingly, receivers of this type include in one form or another a device for suppressing amplitude variations above a predetermined value, which excess variations are caused by static or noise impulses. Such devices are known as "limiters" and consist principally of one or more amplifier stages operated under conditions of poor efficiency so that the gain per stage is necessarily low and the stage will overload when a signal of any magnitude is applied to it. Usually these stages include resistor-condenser net works in the amplifier tube grid return. Various disadvantages are inherent in the above type of limiter. It is not able to follow rapid impulses, because of the time consumed in discharge of the condenser through the resistances, and hence is not effective to suppress short duration impulse noises. Also, there is a tendency, after becoming severely overloaded, for the limiter output to diminish instead of remaining constant.

An object of the present invention is thus to overcome these difficulties by providing a limiter circuit that will completely suppress all excessive amplitude variations, and which will be inherently rapid in response and hence will suppress noise impulses of short, as well as long, duration.

In the limiter of the present invention, the resistance-condenser network is omitted and a feed-back between output and input utilizing non-linear impedances is provided for insuring degeneration of the amplifier tube when the amplitude variations exceed a predetermined value. In accordance with the invention the non-linear impedances are used to pass current through the feed back when the output potentials exceed a certain value, and these currents operate to degenerate the input voltage.

For a better understanding of the invention reference may be had to the accompanying drawings of which:

Fig. 1 is a diagrammatic circuit drawing of a limiter circuit embodying the invention and in

which non-linear impedances are utilized for impressing degenerative potentials on the control grid of the amplifier when the output potentials exceed the limiting value;

5 Fig. 2 is a diagrammatic circuit drawing of a limiter circuit similar to that of Fig. 1 but showing the non-linear impedances arranged for impressing degenerative potentials on a grid other than the control grid of the amplifier; and

10 Figs. 3 and 4 are circuit drawings of limiter circuits similar to Fig. 1 but wherein the feed-back operates inductively upon the input circuit of the amplifier.

In the different drawings like elements are indicated by the same reference numerals or letters.

The limiter circuit of Fig. 1 includes the amplifier tube 2, which may be of any well-known type, preferably one having a screen grid, as for example, the 6SD7GT. A suitable input circuit for the tube 2 is indicated as the conventional tuned circuit having the inductance L bridged by the condenser C, the circuit being grounded at one end and connected to the control grid 4 at the other end. A biasing circuit including a resistance R₁ and bridging condenser C₁ is connected to the cathode 6 of the tube 2 and the plate 8 of the tube is connected to the positive voltage through the load Z, here shown as a resistance. Output connection for the plate circuit is indicated at 10.

A pair of diodes, specifically shown in Fig. 1 as elements within a single tube of the type known as a 6H6, have an anode 12 of one diode 35 and a cathode 14 of the other diode tied together and connected by a lead 15 to the control grid 4 of the tube 2. The anode 16 of the last mentioned diode is connected through a radio frequency choke 18 with the negative terminal of a battery 20, the positive terminal of which is grounded, and the cathode 22 of the first mentioned diode is similarly connected through a radio frequency choke 24 to the positive terminal of a battery 26, the negative terminal of which is grounded. Cathode 22 and anode 16 are connected to the plate 8 of tube 2 through blocking condenser C₂ and C₃, respectively.

The operation of the circuit of Fig. 1 will now be described. Radio frequency signal voltage appearing across the input or tank circuit LC is applied to the control grid 4 of the amplifier tube 2, whereupon current flows in the plate circuit including the resistance Z, the voltage across which becomes available for application to a succeeding amplifier tube. The voltage across Z

will be many times greater than the input voltage across LC , and as the input voltage increases, the output voltage will correspondingly increase until the potential applied to the diodes is sufficient to override the polarizing potentials applied thereto by the batteries 20 and 26. When this occurs, the diodes permit passage of current therethrough and a part of the output current is thus fed back into the grid circuit in such a manner as to cancel and override the input potential from the circuit LC . Because of this cancellation effect, technically known as degeneration, the voltage in the output circuit ceases to respond to increases in input potential amplitude and consequently all amplitude variations above the threshold value, determined by the polarizing potentials applied to the diodes, are eliminated. Assume, for example, that the amplification of the stage is 100, then for .1 peak volt radio frequency applied to the grid 4, there will be a 20 voltage across Z of 10 peak volts radio frequency. If the polarizing potentials applied to the diodes is likewise 10 volts, then there will be no degeneration until the voltage across Z exceeds this value. Any attempt to raise the input voltage above .1 peak volt will not increase the output voltage, because any rise therein over the threshold value immediately results in the feeding back of current through the diodes to the grid 4 in phase opposition to the voltage of the input circuit. Thus the diodes operate as a cyclical voltage gate to pass current during such part of any cycle as the voltage exceeds a predetermined value.

The purpose of the blocking condensers C_2 and C_3 is to keep the D. C. potential of the plate supply from the diodes, and the purpose of the radio frequency chokes 18 and 24 is to keep the resistance of the D. C. return path of the diodes at a minimum in order that the system may respond with alacrity. By tying the anode 12 of one diode and the cathode 14 of the other diode together and by applying negative potential with respect to ground to the anode 16 and positive potential with respect to ground to the cathode 22, the limiter network is made to respond to both halves of the radio frequency pulsations.

The circuit of Fig. 2 differs from that of Fig. 1 in that the degenerative potentials, instead of being applied to the control grid of the amplifier, are applied to a separate grid. In Fig. 2 the amplifier tube 2a is shown as a pentode, and the lead 15a connected to the anode 12 and cathode 14 of the diodes is connected to a grid 28 of the tube 2a. A radio frequency choke 30 grounded at one end and connected to the lead 15a at its other end provides the D. C. path to ground from the diodes. In Fig. 1 the inductance of the tank circuit LC provided the D. C. path to ground. The operation of the circuit of Fig. 2 is similar to that of Fig. 1 and hence requires no additional description.

The circuit of Fig. 3 differs from those of Figs. 1 and 2 in that the feed back through the diodes inductively applies the degenerative potentials to the input circuit of the amplifier tube 2. For this purpose the lead 15b connected to anode 12 and cathode 14 includes a coil L_2 electromagnetically coupled with the tank circuit inductance L . In the particular circuit of Fig. 3 the output load impedance is shown as a tuned circuit including an inductance L_4 bridged by a condenser C_4 . The load impedance of Fig. 3 could, if desired, be a resistance such as Z of Figs. 1 and 2, or could be a radio frequency choke. With the feed-back con-

nected as in Fig. 1, however, a tuned circuit for the output load impedance would not be practicable because the circuit would have a tendency to oscillate. This is because at frequencies below its natural period the tuned circuit will exhibit magnetic reactance and shift the phase of the feed-back voltages applied to the grid so as to make them no longer degenerative.

In Fig. 4 the non-linear impedance is shown as comprising a pair of triodes 32 and 34, and the feed back voltages are impressed upon the tank circuit by means of the inductive coupling including the inductance L_5 in the line 15c. Line 15c is connected at one end to high positive potential indicated on the drawings by "B+" and at the other end to the anodes 36 and 38 of the tubes 32 and 34, respectively. Cathode 40 of tube 32 is grounded while the grid 42 of this tube, which is connected through condenser C_2 to the plate 8, is given a negative bias by connection through a radio frequency choke 44 to the negative terminal of a battery 46, the positive terminal of which is grounded. The grid 48 of tube 34 is also connected to the negative terminal of the battery 46. The cathode 50 of tube 34 is connected through blocking condenser C_3 with the plate 8 and to the ground through the radio frequency choke 52. In Fig. 4 the output load impedance is shown as in Fig. 3, as comprising the tuned circuit L_4 , C_4 .

In operation of the circuit of Fig. 4, current will be passed by the tubes 32 and 34 when the voltage across the output circuit is sufficient to overcome the negative grid bias of the tubes afforded by battery 46. This current, through the inductive coupling L_5 , L applies degenerative potentials to the input circuit of the tube 2 as in the embodiment of the invention illustrated in Figs. 1 to 3 inclusive.

In Fig. 4, as above described, the non-linear impedance comprises the separate triodes 32 and 34. Obviously the elements of these tubes could be combined in a single tube, as for example, a 6C8G or 6F8G.

In Figs. 1 to 4 the polarizing supplies for the diodes are shown as batteries, but the power supply of the usual radio receiver could as well be used, provided care is taken to keep the internal resistance thereof reasonably low, say of the order of a few hundreds of ohms or less.

From the above description of the circuit diagrams of Figs. 1 to 4 it will be apparent that the invention provides an efficient and rapidly operating limiter circuit for receivers of frequency modulated radio waves. In each case degeneration of the amplifier input is insured whenever the output voltage exceeds the threshold value and this degeneration is controlled by a non-linear impedance in the feed-back circuit operating as a cyclical voltage gate which opens at output voltages above the threshold value to pass current for impressing degenerative potentials on the input circuit. The particular non-linear impedances illustrated in the drawings are diodes and triodes but obviously other devices, such as crystal detectors or rectifiers, could be substituted therefor.

I claim:

1. A limiter circuit for frequency modulated radio receivers comprising in combination an amplifier, input and output circuits therefor, said output circuit comprising a resistive impedance, a feed back circuit interconnecting said input and output circuits, a one-way conducting element in said feed back circuit, means for apply-

ing a biasing potential to said element for preventing passage of current therethrough until the output voltage in one direction exceeds said biasing potential.

2. A limiter circuit according to claim 1 including a second one-way conducting element in said feed back circuit, said second element being oppositely connected in said feed back circuit, means for applying a biasing potential to said element for preventing passage of current therethrough until the output voltage in the other direction exceeds said last mentioned biasing potential whereby when the output potential exceeds a predetermined value degenerative potentials are impressed upon said input circuit during both peaks of the voltage wave.

3. A limiter circuit for radio receivers comprising an amplifier, an input circuit and an output circuit therefor, a pair of diodes, means connecting the anode of one diode and the cathode of the other diode together and to said input circuit, means for applying a positive biasing potential to the cathode of the first mentioned diode and for applying a negative biasing potential to the anode of the last mentioned diode, and circuit connections, exclusive of said biasing means, between the output circuit and said last mentioned anode and cathode whereby, when the output voltage exceeds the potentials applied to said diodes, current will be fed back therethrough to the input circuit.

4. The limiter circuit according to claim 3 wherein the degenerative potentials created by the currents passed by the diodes are impressed directly on the amplifier control grid.

5. The limiter circuit according to claim 3 wherein said amplifier includes a plurality of grids and wherein the degenerative potentials created by the currents passed by the diodes are impressed on a grid of the amplifier other than the control grid.

6. The limiter circuit according to claim 3 wherein the degenerative potentials created by the currents passed by said diodes are inductively impressed upon said input circuit.

7. A limiter circuit for radio receivers comprising an amplifier, an input circuit and an output circuit therefor, a feed back circuit between the output and input circuits, a pair of triodes in said feed back circuit having their anodes connected together, a source of positive potential for the anodes of said triodes, the grid of one of said triodes being connected to the output circuit, means for applying a biasing negative potential to the grids of both triodes, the cathode of the other triode being connected to the output circuit and the cathode of the first mentioned triode being grounded, whereby when current is passed by said triodes degenerative potentials are impressed upon said input circuit.

8. In a frequency-modulation amplifier and limiter circuit a high-gain vacuum tube having input and output electrodes, an input circuit connected to the input electrodes and an aperiodic output circuit connected to the output electrodes; a negative feed-back path connected between said output and input circuits, said path provided by a bilateral independent voltage-gate biased to become substantially 100% conducting when the output voltage exceeds a predetermined level during any half cycle.

9. A limiter circuit for frequency modulated radio receivers comprising in combination a high gain radio frequency amplifier having a cathode, a control grid and an anode, an input circuit connected across the grid and cathode of said amplifier, an output circuit including a resistive impedance connected to the anode of said amplifier, a feed back circuit connecting the grid and the anode of said amplifier, said feed back circuit including two oppositely connected one-way conducting elements, means for applying a biasing potential to one of said elements for preventing passage of current therethrough until the voltage across said impedance in one direction exceeds said biasing potential and means for applying a biasing potential to the other of said elements for preventing passage of current therethrough until the voltage across said impedance in the other direction exceeds said last mentioned biasing potential.

10. The limiter circuit according to claim 9 wherein each of said one-way conducting elements is a diode having one electrode connected directly to the grid of said amplifier and the other electrode connected to the means for applying biasing potential to that element and to the anode of said amplifier, condensers interposed between the anode of said amplifier and said last mentioned electrodes of said diodes and radio frequency chokes interposed between the biasing means and the last mentioned electrodes of said diodes.

11. A limiter circuit for frequency modulated radio receivers comprising in combination a high-gain radio frequency amplifier, input and output circuits connected therewith, feed-back means connecting said circuits for impressing degenerative potentials on the input circuit when the output voltage during any part of a cycle exceeds a predetermined value, said feed-back means including independent non-linear impedances, means including a source of potential for biasing said impedances to render them non-conducting until the output voltage exceeds the predetermined value and means connected with said source for preventing the passage of radio frequency current thereto when said impedances are conducting while providing minimum resistance to the passage of direct current.

CARL E. ATKINS.
